US00D776642S

(12) **United States Design Patent** (10) **Patent No.:** **US D776,642 S**
(45) **Date of Patent:** **** Jan. 17, 2017**

(54) **COMBINED HEADPHONE AND AUDIO
PLAYER**

- (71) Applicant: **Sony Corporation**, Tokyo (JP)
(72) Inventors: **Yusuke Otani**, Kanagawa (JP); **So
Morimoto**, Saitama (JP); **Taku
Yaegashi**, Tokyo (JP)
(73) Assignee: **Sony Corporation**, Tokyo (JP)
(***) Term: **15 Years**
(21) Appl. No.: **29/539,977**
(22) Filed: **Sep. 18, 2015**

Related U.S. Application Data

- (60) Division of application No. 29/496,002, filed on Jul. 8, 2014, now Pat. No. Des. 745,862, which is a continuation-in-part of application No. 29/421,750, filed on Sep. 14, 2012, now Pat. No. Des. 709,051, which is a continuation-in-part of application No. 29/371,743, filed on Aug. 18, 2011, now Pat. No. Des. 667,817.

(57) **CLAIM**

The ornamental design for a combined headphone and audio player, as shown.

DESCRIPTION

FIG. 1 is a perspective view of a first embodiment of a combined headphone and audio player showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is perspective view of a second embodiment of a combined headphone and audio player showing our new design;

FIG. 9 is a front elevational thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

1 Claim, 10 Drawing Sheets
